SORTING MACHINE FOR RECORD CARDS

Hans Hacker, Schwabach-Limbach, near Nurnberg, Germany, assignor to Michael Maul, Schwabach, near Nurnberg, Germany

Application January 2, 1959, Serial No. 54,012

Term of patent 14 years

(Cl. D26—5)

Fig. 1

Fig. 2

Fig. 3

Fig. 4

Fig. 5

Fig. 1 is a front perspective view looking at the right thereof of a sorting machine for record cards showing my new design;

Fig. 2 is a top plan view;

Fig. 3 is a rear elevational view;

Fig. 4 is a right side elevational view; and

Fig. 5 is a left side elevational view thereof.

The dotted line portions of the drawing are for illustrative purposes only.

I claim:

The ornamental design for a sorting machine for record cards, as shown and described.
